CLAIM

The ornamental design for a system for audiovisual performances, as shown and described.

DESCRIPTION

FIG. 1 is a side perspective view of a system for audiovisual performances;

FIG. 2 is a side perspective view thereof;

FIG. 3 is a top perspective view thereof;

FIG. 4 is a top plan view thereof;

FIG. 5 is a top and side perspective view of performance area of the system of FIG. 1; and,

FIG. 6 is a bottom and side perspective view from an audience point of view of the system of FIG. 1.
